UNITED STATES PATENT OFFICE.

CHARLES F. GOLDBECK, OF PHILADELPHIA, PENNSYLVANIA.

DEVICE FOR ROLLING OR WRAPPING COIN.

SPECIFICATION forming part of Letters Patent No. 672,325, dated April 16, 1901.

Application filed September 22, 1900. Serial No. 30,795. (No model.)

To all whom it may concern:

Be it known that I, CHARLES F. GOLDBECK, a citizen of the United States, residing in the city and county of Philadelphia, State of Pennsylvania, have invented a new and useful Improvement in Devices for Rolling or Wrapping Coin, of which the following is a specification.

My invention consists of a device for rolling or wrapping coin, the same embodying means for supporting the wrapping material and the block of coin thereon and steadyng the block at the ends thereof.

It also consists in adapting end-steadying means to be adjusted as to the different centers of coins.

It further consists of a gage and guide for the wrapping material, the same being adjustable in width relatively to the length of the block of coin.

It also consists of novel details of construction, as will be hereinafter set forth, and pointed out in the claims.

Figure 1 represents a top or plan view of a coin rolling or wrapping device embodying my invention. Fig. 2 represents a longitudinal vertical section thereof on line $x-x$, Fig. 1. Fig. 3 represents a transverse vertical section of a portion on line $y-y$, Fig. 1. Fig. 4 represents a bottom plan view thereof. Fig. 5 represents a transverse section of a portion on line $z-z$, Fig. 4.

Similar letters of reference indicate corresponding parts in the figures.

Referring to the drawings, A designates a frame or casing in which are mounted the transversely-extending parallel rollers B.

C designates transversely-extending fingers which are elevated above the space between the two rollers and project toward each other, they being supported on the arms D, which are guided in the boxes E on the sides of the casing A. The lower portions D' of said arms are pivotally connected, as at D², with the inner ends of the levers F, which are mounted on the rock-shaft G, which has its bearings on the lower portion of the casing A, the axial portions of said levers having racks H thereon, the same meshing with each other, whereby the levers may be made to simultaneously open and close, and thus impart uniform motions to the arms D, and consequently to the

ingers C. In order to return the levers, and consequently the fingers C, to their first positions, I provide the springs J, portions of 55 which are coiled around the stud K on the rock-shaft G and bear against the pins F' or other proper portions of said levers.

L designates upright plates forming gages and guides for the wrapping-paper employed, 60 the same extending in longitudinal direction over the rollers B at the sides of the top of the casing A and over portions of said top rearwardly of said rollers, where the guards are connected with rack-bars M, each of the 65 latter being guided in a recess N in the top of the casing A and engaged with the pinion P, which is mounted as at N', whereby said rack-bars are geared together and the plates L may be simultaneously moved toward or 70 from each other.

Connected with the casing A, near the top thereof, is the spring plate or catch Q, which is provided with the pin R, the latter being adapted to enter either of the openings S in 75 the adjacent rack-bar M, so as to lock the same, it being noticed that on a plate on the upper side of the casing A are a series of graduations and numbers S' corresponding to the different coins to be rolled, one of the 80 rack-bars M having an indicating-mark T thereon, whereby the plates L may be set to the different lengths of blocks of coins, as will be hereinafter more fully explained.

In the sides of the guards L are openings 85 T', which permit the fingers C to pass therethrough.

U designates a lever which is mounted, as at U', on the side of the casing A, in the present case on the wall of one of the boxes E, 90 and having on its lower end the pin V, which projects freely under the arms D', it being evident that by properly turning the said lever U said pin, and consequently said arms D', may be raised and lowered, thus adjusting the fingers C in height relatively to the centers of different blocks of coins. On the upper side of the box E on which the lever U is mounted is a face-plate W, having graduations and numbers W' thereon, the same being adapted to set the lever U relatively to the denomination of coins to be rolled, it being also noticed that said lever is provided with the pin X, which may enter either of

the openings Y in the box E, so as to retain said lever in adjusted position, said openings registering with said graduations W.

The levers F have connected with them the cords Z, the same being guided on the rollers Z' on the table Z², which is attached to the casing A, whereby the handle ends of the levers Y may be closed by drawing down said cords Z—say by a foot-lever—when so desired.

10 Interposed between the levers F and the table Z² is a spring Z³, whereby when the levers F are lowered by the operation of the treadle said spring serves as a buffer to receive the impact of the levers in their descent 15 and when the treadles are let go to return said levers to their normal positions.

The operation is as follows: The catch Q is withdrawn, so as to release the rack-bars M, and the plates L may be then set to the width 20 of the wrapping-paper. The lever U is also moved so as to elevate the arms D' to the required extent, thus setting the fingers C so as to center the same on the sides of the roll of coin. The levers F are also operated, 25 whereby the fingers C separate, after which a piece of paper or other material suitable for wrapping, as shown dotted at a in Fig. 2, is now placed on the rollers and a block of coin rested on said piece, said roll being shown 30 dotted in said figure, as at b. The levers F are now let go, whereby the fingers C press against the sides of the block of coin at the center thereof, thus steadyng said block and preventing lateral separation thereof. The 35 paper is then wrapped around the block by hand while resting on the rollers B and guided by the plates L, forming a true and perfect cylinder of the paper. The fingers are next withdrawn from the sides of the block by the 40 operation of the levers F and the ends of the cylinder bent or folded down over the sides of the block, and thus the coin is enveloped or wrapped, it then being removed from the rollers, when the operation of wrapping another block may be repeated, it being noticed 45 that the plates L may be set to blocks of different lengths, owing to the variations in the dimensions of the coin, while the fingers C may be adjustably centered on the ends of 50 the block by properly locating the pin V, due to the operation of the lever U. It will also be noticed that the rear roller B is of greater diameter than the other roller, so as to form a shoulder or rise as an abutment against 55 which the cylinder abuts, so that the latter is prevented from displacement while being rolled.

Having thus described my invention, what I claim as new, and desire to secure by Letters 60 Patent, is—

1. In a coin rolling or wrapping device, means for supporting a block of coin, a centering-finger for the end of said block, a carrier for said finger and means connected with 65 said carrier for withdrawing the finger from the block.

2. In a coin rolling or wrapping device, sup-

porting-rollers and centering-fingers, carriers for the latter, and levers attached to said carriers for separating and returning the fingers. 70

3. In a coin rolling or wrapping device, supporting-rollers and centering-fingers, carriers for said fingers, levers attached to said carriers for separating and returning the same, a rock-shaft on which said levers are mounted, 75 and means for raising and lowering said carriers, whereby the fingers may be adjustably centered as to different coin.

4. In a coin rolling or wrapping device, a centering-finger for a block of coin, a rising 80 and falling carrier for the same, and a lever having a member adapted to engage with said carrier, whereby said finger may be vertically adjusted relatively to centers of coins of different denominations. 85

5. In a coin rolling or wrapping device, a centering-finger for a block of coin, a rising and falling carrier for the same, a lever having a member adapted to engage with said carrier, whereby said finger may be vertically 90 adjusted relatively to centers of coins of different dimensions, and a graduated plate for setting said lever.

6. In a coin rolling or wrapping device, a centering-finger for a block of coin, a rising 95 and falling carrier for the same, a lever having a member adapted to engage with said carrier, whereby said finger may be vertically adjusted relatively to centers of coins of different dimensions, a graduated plate for setting 100 said lever, and a locking device for the latter.

7. In a device for rolling or wrapping coin, a casing, rollers mounted thereon, a centering-finger at the side thereof, and means for moving 105 said finger in opposite directions, said casing having a guide for said finger in its lateral motions.

8. In a device for rolling or wrapping coin, a frame, means thereon for supporting a block 110 of coin, a guide for the wrapping material, a carrier for said guide, means for laterally moving said carrier, and a graduated plate on said casing adjacent to said carrier, the latter having an indicating-mark thereon. 115

9. In a device for rolling or wrapping coin, a frame, means thereon for supporting a block of coin, a pair of guiding and gaging plates for the wrapping material, rack-bars and a pinion for simultaneously moving said plates 120 in opposite directions for adjustment to different widths of said material, and a graduated plate on said frame adjacent to either rack-bar, the latter having an indicating - mark thereon. 125

10. In a device for rolling or wrapping coin, a frame, means for supporting a block of coin, plates adapted to be adjusted to wrapping material of different widths, bars connected with said plates, supports on the casing of the device for said bars, means for coupling and operating said bars, whereby the plates may be simultaneously moved in opposite directions for wrapping material of different widths, and 130

means on said frame for locking either of said bars in the adjusted position of said plates.

11. In a device for rolling or wrapping coin, means for supporting a block of coin, a steady-
5 ing member adapted to be centered on the end of a block of coin, a hand-lever for ad-
justing said member to centers of coins of different widths, a rock-shaft on which said

lever is mounted and a cord connected with said lever for operating the latter by a down- 10 ward draft of said cord.
